AUTOMATIC STOKER

Arthur E. Paige, Philadelphia, Pa.

Application May 11, 1938, Serial No. 207,249

4 Claims. (Cl. 110—45)

Letters Patent of the United States No. 2,106,621 was granted to me January 25, 1938, for an improvement in underfeed fire pots, which includes a hollow base for reception of air under pressure, an annular grate extending above said base and formed of a circular series of sectoral grate bars, the edges of which overlap and form air passages between the bars through which air is directed through the grate tangentially in vertical vertical streams. The object and effect of this invention is to provide simple and effective means for positively feeding coal, directly from an ordinary bin, upwardly into such a grate, at a uniform rate which is readily variable by an unskilled user, and insuring that the ashes and any clinkers formed upon the top of the grate shall be discharged from the circumferential edge thereof.

My invention avoids the use of friction driving belts of the prior art, and includes the various novel features of construction and arrangement hereinafter more definitely specified.

In said drawing:

Fig. I is a plan view of an automatic stoker mechanism conveniently embodying my invention; the coal conveying tube and its appurtenances at the left hand end thereof being partly broken away to permit that illustration to be made on a larger scale than if the complete extent of said tube and its appurtenances were shown.

Fig. II is a longitudinal vertical sectional view of the structure shown in Fig. I.

Fig. III is an elevation of the left hand end of the structure shown in Figs. I and II; part of the structure shown at the right hand end of Figs. I and II being broken away in Fig. III.

Fig. IV is a plan view of one of the sectoral grate bars shown in section at the right hand end of Fig. I.

Fig. V is an inverted plan view of said grate bar shown in Fig. IV.

Fig. VI is a fragmentary plan sectional view taken on the line VI, VI in Fig. II, showing the tangential air passages between the grate bars.

In said figures; 1 is a cast iron cap rigidly connected with the cylindrical tube 2 to provide a coal inlet 3 at the left hand end portion of said tube which is there reduced to semi-cylindrical trough shape. Said cap 1 and the tube 2 are extended into a bin, hopper, or other suitable receptacle 4, in which coal may be piled over them, above the floor 4', to gravitate into said tube, at inlet 3.

Coal is conveyed through said tube 2 from said inlet 3, toward the right in Figs. I and II, by means of the reciprocating conveyor plunger bar 5 which has wedge shaped projections 5' adapted to engage comminuted coal and push it to the right but to release the coal and permit the bar to slide through it to the left in Figs. I and II.

As indicated in Fig. III, said wedge shaped projections 5' on the bar 5 are of inverted U-shape. However, the left hand end portion 5'' of said bar is conveniently rectangular in cross section as indicated in dotted lines in Fig. III, and fitted to reciprocate through a similarly shaped bearing in said cap 1 to hold said bar in the upright position shown in Fig. III.

The electric motor 6, which is resiliently connected with the base 7, as best shown in Fig. III; is arranged to reciprocate said coal conveyor bar 5 by providing the extension 8 of the motor armature shaft 8' with the worm 9, shown in Fig. II, in engagement with the gear 10. Said gear is journaled on the stationary stud 11 in the gear box 12 which is rigidly connected with said base 7 and affords bearings for said shaft extension 8 at opposite ends of said worm 9. Said gear 10 has the upwardly extending crank stud 14 rigidly secured therein and carrying the roller 15. Rotation of said worm 9 causes said gear 10 to turn counter-clockwise in said box 12 with the crank 14 and its roller 15 projecting upwardly through the circular opening 16 in the lid 17 of said box 12 which is concentric with the axis of said gear stud 11. Said lid 17 has parallel guide ribs 18 projecting upwardly from the top thereof to guide the slide bar 20 which has the slot 21 fitted over said roller 15, as shown in Fig. II. Said slide bar 20 has the slot 22 fitted over the upwardly projecting flange 23 of said coal bar 5, by which said bar is reciprocated. Said slide bar 20 is rigidly connected by the screw 24 with its supporting tube 25 which is mounted to reciprocate in the bearing 26 of the standard which includes the pair of legs 27 shown in Fig. III. Said screw 24 is axially adjustable through the lug 20' on said slide bar 20 so that the stroke of said bar 20 may be varied in accordance with the amount of coal which it is desired to progress to the right in said coal tube 2 at each stroke of said bar 20.

It is to be understood that the arrangement above described is such that with the screw 24 set in the position shown in Figs. I and II; the slide bar 20 and the coal bar 5 are caused to reciprocate to the full extent of throw of the

crank 14, but, said screw 24 may be adjusted toward the right to permit lost motion of the slide bar 20 with respect to the coal conveyer bar 5 when said bar 20 is moved to the left in Figs. I. 5 and II and thus make the stroke of the coal bar 5 less than the stroke of the slide bar 20 which is constantly that of the throw of the crank 14.

Said coal conveyer tube 2 is rigidly connected with the elbow 28, conveniently by the set screws 10 29, and said elbow supports the hollow base 30 with which it is rigidly connected, conveniently by a circular series of three bolts 31.

As shown in Figs. I and III, said air base 30 has the air inlet 31' in tangential relation to 15 the axis of said base and air under pressure is delivered into said base through the air conveyer tube 32 which is rigidly connected with said inlet 31, conveniently by set screws 34, and also rigidly connected with the outlet 35 of the fan 20 casing 36 in which the fan wheel 37 is carried on the end of the shaft 8.

Air is admitted to said fan casing 36 through the cylindrical tubular inlet 38, in coaxial relation with said shaft 8. The effective area of 25 said air inlet 38 is variably predetermined by the valve disk 39 supported by the axial screw 40 fixed in said disk, which is in engagement with the axial hub nut 41 in the spoked web 42 in the side of said casing 36.

30 Said supporting tube 25, for the slide bar 20, has its right hand end, shown in Fig. II, engaging as a nut, the screw threaded shank of the coupling 25'. As shown in Fig. I, said coupling 25' extends between the bifurcations of the lower 35 end of the link 44 with which it is connected by the pivot bolt 45. The upper end of said link 44 extends between the bifurcations of the bracket 46 with which it is connected by the pivot bolt 47. Said bracket 46 is rigidly connected with the rockable ring 48 which has pivot 40 brackets 49 at diametrically opposite sides thereof mounted to rock on respective pivot stud bolts 50 rigidly connected with the opposite sides of said air base 30, as follows:

45 As shown in Fig. I, the upper rim of said air base 30 has three outwardly projecting lugs 30' with respective bolts 51 extending therethrough holding the ash ring 52 in rigid relation with said air base 30. As shown in Fig. II, the upwardly extending flange 28' on said coal elbow 28 and the circular inner edge of the bottom of said air base 30 rigidly connected therewith afford opposed cylindrical surfaces between which the lower ends of sectoral grate bars 53 are fitted 55 to prevent their displacement in said base 30. Each of said bars 53 has its substantially flat upper end extending beneath said ash ring 52 and resting outwardly against the upper rim of said air base 30 which serves as an annular support for said series of grate bars which form an annular grate in coaxial relation with said air base 30.

Referring to Figs. IV, V, and VI; each of said 60 grate bars 53 has an inwardly convexed surface to support the fuel, and has corrugations 53' extending outwardly along one radial edge of the bar and consequently circumferentially in the grate. The opposite radial edge of each bar is smooth and overlaps the corrugated edge of the 65 adjoining bar, in radially spaced relation so as to form air passages 54 between said corrugations on each bar 53 and between said bars, whereby, air supplied to the interior of said base 30 under pressure from said fan wheel 37 es- 70 capes through the grate to the interior thereof 75

and any fuel thereon, said air passages between the bars directing the air through the grate tangentially in vertical vertical streams.

It is to be understood that the construction above described is such that at each revolution 5 of said worm gear 10 coal is underfed through the coal conveyer tube 2 and elbow 28 to said annular grate and, said ring 48 is rocked to insure that ashes and any clinkers formed at the top of the grate, upon the ash ring 52, shall be 10 discharged downwardly from the circumferential edge of the latter.

As indicated in Fig. II; I find it convenient to form said coal conveyer tube 2 in two sections which are abutted at 2', and connected by 15 two metal straps 55 and four tap bolts 55'. Said sections of tube 2 are respectively rigidly upheld against web 1' of base 7 by U-bolts 56 and 57 provided with nuts above said web. Such construction and arrangement permit the convenient 20 formation of the slot 23' in the left hand end of the right hand section of the coal conveyer tube 2 to receive the vertically extending flange 23 of the coal bar 5. Moreover, I find it convenient to form said coal bar 5 of two or more 25 sections which are rigidly connected by dowel pins 58 having cross pins 59 extending through them. Said coal tube 2 and coal conveyer bar 5 may be made any desired length in accordance 30 with the distance of the supply of coal from the grate.

Furthermore, I prefer to provide the right hand end of said coal conveyer bar 5 with a section 60 which is in articulated relation with the other portion of said bar with which it is 35 connected by the pivot 61. Said section 60 serves as a poker which is not only reciprocated by and with the bar 5 but has an up and down rocking movement beneath the mass of coal in the elbow 28 to insure the proper underfeeding 40 movement thereof into the annular grate.

I also find it convenient to provide the bottom of the air base 30 with the rectangular downwardly extending outlet 62 through which any so-called "fly ash" which may happen to gravitate into the air base may be readily discharged by the compressed air with which said base is supplied by the fan wheel 37. The fly ash outlet 62 is normally closed by the door 63 which is hinged upon the pivot pin 64 in said outlet 50 62 and has the downwardly extending lug 65 for pivotal connection with the right hand end of the door operating rod 67 which is prevented from escaping from said door by the cotter pin 68 extending through the end of said rod. Said 55 rod 67 is supported near its left hand end by the guide plate 70 upheld against the web 1' of the base 7 by the U-bolt 56. As shown in Fig. II, the left hand end of said rod 67 is bent to form the handle 67' and connected by the tension 60 spring 71 with the screw stud 72 in said base 7. The stress of said spring 71 continually tends to hold the door 63 shut in the position shown in Fig. II, but said door may be momentarily opened by the operator pulling said rod 67 by 65 its handle 67' toward the left in Fig. II; whereupon, any "fly ash" in the air base 30 is discharged downwardly therefrom, by a blast of air from said air base 30.

I have not provided any support for said stoker 70 mechanism within the furnace inclosure 73, because any such support would interfere with the removal of ashes from the floor 4'. The legs 27 attached to the coal conduit 2, outside of said inclosure 73, uphold said conduit and the air 75

base, grate, and their appurtenances, with considerable clear vertical space beneath said conduit, to facilitate the removal of ashes from said floor. Moreover, the fly ash outlet 62 is thus upheld, above said floor 41 so that all fly ashes may be delivered through said outlet into the convection air current which is passing upward, above said floor, through said inclosure 73 to the stack, to prevent the ashes from being blown backward out of said inclosure.

I prefer to provide the slotted portion of said slide bar 20 with drilled sockets holding bearing balls 74 and 75 respectively bearing upon the top of said gear box lid 17 and the guide ribs 18, to facilitate the reciprocation of said bar 20. In order to exclude dust from said box; I find it convenient to provide the circular dust guard disk 76 in coaxial relation with said gear 10 and to rigidly connect the same with said gear by the crank stud 14, which has the nut 14' at its top, bearing on said disk. I also mount in the ends of the link 44 circular series of rollers bearing upon the pivot bolts 45 and 47 which are respectively held stationary in said link 44 and in the bracket 46. To eliminate dust from the elbow 28 I provide a group of small sieve holes 28' in the bottom thereof.

However, I do not desire to limit myself to the precise details of construction, arrangement, or method of operation herein set forth, as it is obvious that various modifications may be made therein without departing from the essential features of my invention as defined in the appended claims.

35 I claim:

1. In an automatic stoker mechanism, the combination with an annular grate; of means for underfeeding fuel into said grate, including a tube with an upwardly curved elbow having one end in coaxial relation with said grate, said tube extending radially with respect to said grate; a reciprocating conveyer plunger bar, mounted to reciprocate in said tube; an upwardly extending flange on said conveyer, projecting through a slot in the top of said tube; means for reciprocating said conveyer by said flange, including a slide bar having a slot fitted over said flange, and bearing means rigidly connected with said tube at the top thereof for supporting said slide bar for reciprocation; driving means for reciprocating said slide member with constant amplitude; means for adjustably varying the extent of reciprocation of said conveyer, with respect to said slide bar, including a single, axially adjustable screw mounted in said slide bar for contact with one edge of said flange; means for holding said screw in said slide bar in adjusted position; and means for reciprocating said slide bar; whereby, the rate of feeding fuel to said grate may be varied in relation to the constant speed of said driving means, by merely axially adjusting said single screw.

2. In an automatic stoker mechanism, the combination with an annular grate; of means for underfeeding fuel into said grate, including a tube with an elbow having one end in coaxial relation with said grate, said tube extending radially with respect to said grate; a reciprocating conveyer plunger bar, mounted to reciprocate in said tube; an upwardly extending flange on said conveyer, projecting through a slot in the top of said tube; means for reciprocating said conveyer by said flange, including a slide bar having a slot fitted over said flange, and bearing means rigidly connected with said tube at the top there-

of for supporting said slide bar for reciprocation; driving means for reciprocating said slide bar with constant amplitude, including an electric motor; means for adjustably varying the extent of reciprocation of said conveyer, with respect to said slide bar, including a single, axially adjustable screw mounted in said slide bar for contact with one edge of said flange; means for holding said screw in said slide bar in adjusted position; said means for reciprocating said slide bar, including a worm gear mounted on a vertical axis and having a crank engaging a slot in said slide bar; and a worm on the armature shaft of said motor in mesh with said worm gear.

3. In an automatic stoker mechanism, the combination with an annular grate; of means for underfeeding fuel into said grate, including a tube with an elbow having one end in coaxial relation with said grate, said tube extending radially with respect to said grate; a reciprocating conveyer plunger bar, mounted to reciprocate in said tube; an upwardly extending flange on said conveyer, projecting through a slot in the top of said tube; means for reciprocating said conveyer by said flange, including a slide bar having a slot fitted over said flange, and bearing means rigidly connected with said tube at the top thereof for supporting said slide bar for reciprocation; driving means for reciprocating said slide bar with constant amplitude, including an electric motor; means for adjustably varying the extent of reciprocation of said conveyer, with respect to said slide bar, including a single, axially adjustable screw mounted in said slide bar for contact with one edge of said flange; means for holding said screw in said slide bar in adjusted position; and means for reciprocating said slide bar, including a gear mounted on a vertical axis and having a crank engaging a slot in said slide bar, a worm engaging said gear, and an electric motor operatively connected with said worm; whereby continuous rotary movement of said gear and crank effects reciprocating movement of said slide bar and conveyer plunger, but, the amplitude of movement of said conveyer may be adjustably varied with respect to the movement of said slide bar by adjustment of said single screw.

4. In an automatic stoker mechanism, the combination with an annular grate; of means for underfeeding fuel to said grate, including a tubular conduit in radial relation with the grate and having an upwardly curved elbow with one end in coaxial relation with the grate; a reciprocating conveyer plunger bar, mounted to reciprocate in said conduit; an upwardly extending flange on said conveyer, projecting through a slot in the top of said conduit; means for reciprocating said conveyer by said flange, including a slide bar; bearing means rigidly connected with said tube at the top thereof for supporting said slide bar for reciprocation; driving means for reciprocating said slide bar with constant amplitude; means for adjustably varying the extent of reciprocation of said conveyer, with respect to said slide bar, including a single, axially adjustable screw mounted in said slide bar for contact with one edge of said flange; and means for holding said screw and said slide bar in adjusted position; whereby, the rate of feeding fuel to said grate may be varied in relation to the constant speed of said driving means, by merely axially adjusting said single screw.
